UNITED STATES PATENT OFFICE.

LEOPOLD MYERS, OF BIRMINGHAM, ENGLAND.

DRAWING-COMPASSES.

1,047,275.

Specification of Letters Patent. Patented Dec. 17, 1912.

Application filed September 6, 1911. Serial No. 647,934.

To all whom it may concern:

Be it known that I, LEOPOLD MYERS, a subject of His Majesty the King of Great Britain and Ireland, residing at Charlotte 5 Street Steel Pen Works, Charlotte street, Birmingham, in the county of Warwick, England, pen manufacturer, have invented new and useful Improvements in Drawing-Compasses, of which the following is a specification.

This invention has reference to drawing compasses of that kind which are made to fold for the pocket and consists chiefly in the improved construction and arrangement 15 of the knee joints as hereinafter described which according to this invention are constructed with knife springs adapted to hold the lower portions of the limbs rigidly extended in a line with the upper limbs when 20 in use and also to securely hold said lower limbs folded against the upper limbs when the compasses are closed for carrying in the pocket.

I will describe my invention by referring 25 to the accompanying drawings on which—

Figure 1 is a front elevation partly in section of drawing compasses constructed in accordance with this invention, this view showing the compasses open ready for use; 30 Fig. 2 is a side elevation of the left hand leg of Fig. 1 looking toward the inside of same; Fig. 3 is a sectional plan of this leg taken on line X X of Fig. 1; Fig. 4 is a front elevation of the compasses shown in Fig. 1, 35 but folded; Fig. 5 is a front elevation of one of the knife springs of the said compasses; Fig. 6 is a sectional plan through Fig. 5 taken on line Y Y. Fig. 7 is a plan of the sheet steel blank from which the knife 40 spring shown in Fig. 5 has been formed; Fig. 8 is a side elevation and Fig. 9 is a plan of the pencil socket limb of the said compasses; Fig. 10 is a side view of the said pencil socket limb; Fig. 11 is a plan of the sheet 45 metal blank from which the pencil limb shown in Figs. 8, 9 and 10 has been formed, and Fig. 12 is a plan of the sheet metal blank for forming the point limb of said compasses.

In carrying out this invention the lower limb 1 of the point leg of the compasses is 50 at the joint pin 2 (which connects this lower limb 1 to the upper limb 3) made with two flat edges marked respectively 4 and 5 and 55 also with a flat end 6. Fixed to the upper limb 3 of this leg there is a knife spring 7

something like the spring in the back of a pocket knife, the free end 8 of which acts against any of the flat portions 4, 5 and 6 of the lower limb 1 and will thus maintain 60 the said lower limb turned outwardly in a line with the upper limb, as in Fig. 1, or folded back up against the same as in Fig. 4, the action of the knife spring 7 on the lower limb 1 of the leg being similar to the 65 action of a pocket knife spring on its blade. The upper limb 3 to which the knife spring 7 is fixed is by preference although not necessarily made of a sheet metal blank bent into a U section with two ears at the top jointed 70 on to the center joint 9 as usual and with the upper end of the lower limb 1 fitting and jointed between the two sides 10, 11 of the U between which the knife spring 7 is situated and thus the latter is practically concealed 75 from view.

The knife spring 7 is by preference although not necessarily made of an elongated sheet steel blank such as shown in Fig. 7 which is folded along its longitudinal center line 12, the halves being pressed together so as to make the spring of double thickness of metal as shown in Fig. 5 with the folded edge 13 at the back of the spring. Thus a spring of sufficient stiffness and elasticity is 85 formed which does not require to be hardened and tempered. The knife spring 7 fits between the two sides of the U section leg 3 and is there secured by any convenient means but preferably by the upper end of 90 the knife spring having a recess 14 at one edge formed by the blank Fig. 7 showing two of these recesses 14 in opposite sides of the blank, so that when the spring is placed in the U section leg stout tongue like portions 95 15, 16 projecting from the sides of the U section leg 3 are bent and closed over into these recesses 14 thereby forcing the folded part of the spring against the back of the inside of the trough section leg and securely 100 holding the spring in position.

The knife spring 7 is made taper, that is, of less thickness at its outer end 8 than at its fixed end 17 and there is a certain amount of clearance at 18 between the lower end 8 of 105 the knife spring and the underside of the lower end of the U section leg 3 to permit of the spring being forced back by the corners or heels 19 of the upper part of the lower limb 1 as it is being turned from its 110 extended position Fig. 1 to its folded position Fig. 4 or vice versa. It is to be under-

stood that the pencil leg 21 is fitted with a knife spring 7 to retain the pencil limb 20 in its open and closed positions similarly as above described with reference to the knife 5 spring 7 of the leg 3 for acting on the point limb 1.

Both the point limb 1 and the pencil limb 20 of the said compasses are by preference each made of a sheet metal blank of suitable 10 shape about twice the width of the required limb and folded longitudinally upon itself so as to make a limb of double thickness with a nice rounded edge. The blank for forming the pencil limb is shown separately 15 in Fig. 11 by which it will be seen that the blank has its top part 22 made with two vertical parallel side edges 5 and a flat top part 6 at right angles thereto so that when the blank is folded along its longitudinal 20 center line 23 the two edges 5 will come together to form the corresponding flat edge on the top part of the limb the folded side 23 forming the other flat side 4. The portion 24 of the blank shown in Fig. 11 corre- 25 sponds with twice the width of the main portion of the limb 20 and this part 24 terminates in two inclined side wings 25, 26 which being raised to somewhat of a semi-circular form in cross section form the pen- 30 cil socket when the blank is folded upon itself on its longitudinal center line 23 as in Figs. 8, 9 and 10, the folded or rounded edge 27 of the blank being on the inside of the compasses with the divided pencil socket 35 formed by the parts 25, 26 projecting at the proper angle to receive and hold the pencil. The sheet metal blank 28 for forming the point limb which is shown by Fig. 12 is folded upon itself upon its longitudinal cen- 40 ter line 29 so as to make a limb of double thickness as aforesaid with a nice rounded back edge 30 and with the point 31 held in position by being gripped between the two sides of the blank when closed around the 45 same, the blank being made with two upwardly projecting square shaped ears 32 at a short distance apart which when the blank is folded as aforesaid come together face to face to form the required square shaped top 50 of the limb and with the flat side 4 set back for some distance from the rounded edge 30 to accommodate the end 8 of the knife spring as in Fig. 1.

What I claim as my invention and desire to secure by Letters Patent is:—

55

1. In a drawing compass, in combination, upper limbs pivotally connected to one another at their upper end, said limbs being of U-shaped cross section, knife springs positioned and inclosed within said U-shaped 60 limbs, each of said springs having its upper end fixed to its associated limb and its lower end free, and lower limbs pivoted to the lower ends of said upper limbs, said lower limbs being provided with flat portions 65 adapted to be engaged by said springs, whereby said lower limbs will be held in position.

2. In a drawing compass, in combination, upper limbs pivotally connected to one another at their upper end, said limbs being of U-shaped cross section, knife springs positioned and inclosed within said U-shaped 70 limbs, each of said springs having its upper end fixed to its associated limb and its lower 75 end free, and lower limbs pivoted to the lower ends of said upper limbs, said lower limbs being provided with flat portions adapted to be engaged by said springs, whereby said lower limbs will be held in po- 80 sition, each of said lower limbs comprising a sheet of metal folded upon itself and pro- vided at its lower end with a socket.

3. In a drawing compass, in combination, upper limbs pivotally attached to one another at their upper ends, said limbs being of U-shaped cross section, knife springs positioned and inclosed within said U-shaped 85 limbs, each of said springs being provided adjacent its upper end with a recess, each limb being provided with a portion bent to extend within the recess formed in the knife associated therewith to hold it in position, the lower ends of said knife springs being free, and lower limbs pivoted to the upper 95 ends of said upper limbs, said lower limbs being provided with flat portions adapted to be engaged by said springs, whereby said lower limbs will be held in position.

In testimony whereof I have signed my 100 name to this specification in the presence of two subscribing witnesses.

LEOPOLD MYERS.
